Patented Mar. 8, 1921.

Application filed October 13, 1920. Serial No. 416,769. Term of patent 14 years.

To all whom it may concern:

Be it known that I, HARRY HAUPT, a citizen of the United States, residing at Elmsford, in the county of Westchester and State of New York, have invented a new, original, and ornamental Design for a Pad-Calendar Holder, of which the following is a specification, reference being had to the accompanying drawings, forming a part thereof, and in which—

Figure 1 is a side elevation;

Fig. 2 a top view, and

Fig. 3 a front elevation of a pad calendar holder embodying my design.

I claim:

The ornamental design for a pad calendar holder, as shown.

HARRY HAUPT.
